UNITED STATES PATENT OFFICE.

THOMAS A. LADSON, OF TAMPA, FLORIDA.

DESIGN FOR A SPOON.

45,812.

Specification for Design.

Patented May 19, 1914.

Application filed March 23, 1914. Serial No. 826,821. Term of patent 7 years.

To all whom it may concern:

Be it known that I, THOMAS A. LADSON, residing at Tampa, in the county of Hillsboro and State of Florida, have invented a certain new, original, and ornamental Design for a Spoon, of which the following is a specification, reference being had to the accompanying drawing, forming part thereof.

Figure 1 of the drawing is a view of the obverse side of my new design for a spoon;

Fig. 2 is a view of the reverse side thereof; and Fig. 3 is a sectional view of a portion of the handle.

I claim:

The ornamental design for a spoon, as shown.

THOMAS A. LADSON.
